RECORD CABINET DEVICE

Lloyd M. Toms, Crozet, Va., assignor to Acme Visible Records, Inc., Crozet, Va., a corporation of Delaware

Filed Apr. 25, 1960, Ser. No. 24,331

4 Claims. (Cl. 312—303)

This invention relates to improvements in record cabinet devices.

More particularly, the present invention relates to filing cabinets wherein the cabinet houses a plurality of superimposed drawers or trays, each drawer or tray being carried by a slidably mounted support means. These support means are adapted to move outwardly of the cabinet front to a limited distance, with the trays remaining pivotally engaged thereto and then adapted to be inclined for operative access to record means carried by the trays.

The movable support means above referred to include channel members opening toward each other within which are engaged fixed pivots extending laterally from the inner ends of the trays. These trays are further adapted to be engaged to and disengaged from the channel members by means of slots or notches formed in the upper flange portions of the channel members which receive the pivot pins. Although there is generally no difficulty encountered in accidental disengagement of the trays from the channel members with which they are associated when the trays are fully extended and inclined in operative position, it has been found that when returning the trays to nested position in the filing cabinet, which comprises elevation of the tray from inclined to horizontal position, that during the initial movement of returning the tray to within the cabinet at times the tray becomes unintentionally disengaged by reason of its pivot pins accidentally becoming elevated through the slots and disengaged from the channel members.

It is therefore an object of the present invention to provide pivot pins for the trays of novel contour or cross-sectional shape so that although these pins may be passed through the slots in the channels as aforesaid for engagement and disengagement, this cannot be done when the tray is in an inclined position and only when it is in a substantially horizontal position.

Other objects and advantages of the invention and the details of construction and arrangement of parts thereof will be apparent from the following specification and accompanying drawings, wherein:

FIG. 1 is a perspective view of a record card filing cabinet embodying the present invention and illustrating one of the component trays thereof in withdrawn and operatively inclined position.

FIG. 2 is a fragmentary perspective exploded view, with parts broken away, of a tray and its pivot pins and the cooperative supporting means therefor, in accordance with the present invention.

FIG. 3 is an enlarged fragmentary detail view on the line 3—3 of FIG. 2.

FIG. 4 is a fragmentary view of the interior side face of the cabinet of FIG. 1; and

FIG. 5 is a fragmentary transverse sectional view of the side wall of the cabinet of FIG. 1.

Referring to the drawings, the reference numeral 10 generally indicates a record filing cabinet to which the improved means of the present invention are adapted. This cabinet comprises a pair of opposed side walls 11, 11, the inner faces of which include a plurality of wall channel members comprising web portions 12 and flange members 13 secured by the leg component 14 to the wall 11. These wall channel members are formed with a plurality of horizontally extending struck-up guide members 15 extending upwardly and the members 16 extend-

2

ing downwardly, between which are slidably supported tray supports 17. These tray supports are slidable on the guides 15 and 16 to a limited degree determined by the terminal inturned stop members 18 and 19, respectively, which abut against the resilient pads 20 and 21, respectively, engaged to the members 13 whereby movement of the tray support 17 is limited outwardly of the cabinet by the stop member 18 and inwardly thereof by the stop member 19.

Although only one of the side walls 11 is shown in detail in FIGS. 4 and 5, it will be understood that each side is formed in a similar manner so that a pair of opposed tray supports 17 each carries a runner channel member comprising a web portion 22 secured to the tray support 17 and opening toward each other, each runner channel being endwise closed at its forward end as at 23 and being formed with a slot or notch 24 in the upper flange 25 thereof, this closed forward end portion of the runner channel member and its notch 24 being adapted to project forwardly of the front end of the cabinet 26 as, for example, shown in the detail view of FIG. 4 to the limit of the stop member 18, and adapted to be return-nested within the cabinet to the limit of the stop 19 as shown in FIG. 5.

A pair of lower flanges 27, integral with the webs 22 of the runner channels carried by a pair of tray supports 17, form a support for a slideable tray 28 which has fixedly secured thereto at its rearward end a rod 29 which terminates in the opposed laterally extending pivot pins 30, 30. Each of the plurality of horizontally stacked members 28 is supported on opposed pairs of wide flange members 27. The forwardly projectable end portions of these flanges 27 are recessed or set back as at 31 so that when a tray 28 is withdrawn from the cabinet 10 to the extent where its pivot pins 30 abut against the closed ends 23 of the runner channels, and the runner channels are drawn forwardly to the limit of the tray support stop members 18, a tray 28 can be caused to incline downwardly and forwardly of the recessed flange portions 31 and forwardly of the face 26 of the cabinet—for example, to rest in an inclined position against the shelf 32 carried near the base of cabinet 10 as shown in FIG. 1.

When so inclined, access may be had to the record means carried by the trays, such as a plurality of cards 33 mounted in edgewise-spaced, overlapped engagement with each other by means of their hinges 34 mounted on the flexible metal hangers 35, the opposed ends of which are disposed and retained beneath the flanges 36 on the trays 28.

As shown in FIG. 2 and the full view in FIG. 3, the pivot pins 30 are of such contour that they cannot pass through the slots or notches 24 when the trays 28 are inclined to the horizontal, and thus in such position the trays or rather their pivot pins 30 cannot be withdrawn through the notches 24 in the upper flange 25 of the tray supporting runner channels. However, as appears from the dotted position in FIG. 3, the contour of the pivot 30 is such that when a tray 28 is disposed in substantially horizontal position it may be readily passed through the slot 24. This may be done by shaping the pivot pin in a manner so that it will accomplish the foregoing function. As shown in the illustrative drawings, one means for accomplishing this is by flattening the normally cylindrical shape of the pins 30 so that they will be out of round or flattened with the top side of the flat parallel to the tray slide flange 27 when the tray is at its normal inclined reference angle. That is to say, the flattening of the normally cylindrical pin spreads it so that it is wider than the slot 24 and therefore cannot jump out of the slide when the tray is pushed at an incline to return it to within the cabinet.

However, when the tray is disposed horizontally the

narrower dimension of the flattened pin will pass easily through the slots 24 and thus will permit ready insertion or removal of the tray from the cabinet at a desired time, rather than just accidentally. Although the view of FIG. 2 shows the pin 30 flattened on the top as viewed in said figure when the tray 28 is inclined, with the remaining portion of the pin rounded, the view of FIG. 3 for clarity shows an optional form in that the pivot pin portion 30 has opposed faces substantially parallel and flattened.

As previously indicated, however, any pivot pin 30 contour may be employed which will accomplish the aforesaid function of being unable to pass through a slot 24 when a tray 28 is inclined in operative position, and such that it can pass through the slot 24 when the tray is disposed in substantially horizontal position.

I claim:

1. In a file cabinet the combination of a tray provided with fixed pivots of flattened cross-section, a pair of tray supports having channel members opening toward each other and receiving said pivots and mounted in said cabinet for limited slidable engagement therein and to permit projection of said channels forwardly of said cabinet, the forward ends of said channels being closed and their forwardly projectable portions being formed with notches in their upper flange portions, said flattened pivots being angularly disposed relative to the plane of said tray whereby they present a profile adapted to pass through said notches when the tray is in a substantially horizontal position and a profile of greater width than said notches when said tray is inclined to the cabinet for prevention of accidental disengagement in the latter position.

2. In a cabinet having a removable tray endwise engaged by pivot pins fixedly secured to and extending laterally from the rear terminal end of the tray into opposed channel members opening toward each other and forwardly endwise closed, said channel members normally supporting said tray in horizontal disposition on lower flange extensions of said channels inwardly of said closed forward channel ends, and supports for said channels in limited slidable engagement with said cabinet for permitting the forward end portion of said channels to be projected outwardly of the front of the cabinet and the engaged trays to be thereupon pivoted downwardly at an

10
5

incline thereto for operative access, the upper flanges of said channels being formed with notches for receiving said tray pivot pins for engagement and disengagement of said trays with said channel members, said pins being of nonuniform cross-section adapted to be moved through said notches when the tray is in a substantially horizontal position and of oversize dimension for passage through said notches when the tray is in an inclined position whereby to prevent accidental disengagement of an engaged tray.

3. In a file cabinet of the class described the combination of a drawer provided with pivots of noncircular cross-section, a pair of tray supports having channel members opening toward each other and receiving said pivots and mounted for limited projection forwardly of said cabinet, the forward ends of said channels being closed and their forwardly projectable portions being formed with notches in their upper flange portions, said pivots being secured relative to said tray whereby they present a profile adapted to pass through said notches when the tray is disposed in a substantially horizontal position and a profile of greater width than said notches when said tray is inclined to said tray supports.

4. In a file cabinet the combination of a tray including pivots of flattened cross-section and a pair of tray supports having channel members opening to each other and receiving said pivots, the forward ends of said channels being closed and their adjacent end portions being formed with notches in their upward flange components, said flattened pivots being fixedly secured relative to said tray with their flat faces at an angle to the plane thereof whereby they present a profile adapted to pass through said notches when the tray is disposed in substantially parallel relationship to the channels and a profile of greater width than said notches when said tray is inclined to the channels.
